(57) **CLAIM**

The ornamental design for spokes for an automotive wheel, as shown and described.

DESCRIPTION

FIG. 1 is a top front perspective view of spokes for an automotive wheel showing my new design;

FIG. 2 is a top back perspective view thereof;

FIG. 3 is a front elevation view thereof;

FIG. 4 is a rear elevation view thereof;

FIG. 5 is a right elevation view thereof, with a left elevation view being a mirror image of the right elevation view; and, FIG. 6 is a top elevation view thereof, with a bottom elevation view being a mirror image of the top elevation view.

The broken lines shown in the drawings depict portions of the article that form no part of the claimed design.
